Letters Patent

The Schedule referred to in the Letters Patent and making part of the same containing a description in the words of the said Amos Minor himself of the improvement in Water Pumps.

Be it known that I Amos Minor of the Town of Elbridge, County of Onondaga and State of New York have invented a new and useful improvement in Water Pumps and that the following is a full and exact description thereof. The working cylinder in which the plunger or piston operates, is made of cast iron except in case when the fountain from which the pump draws, is liable to become frequently dry in which case a composition formed of zinc and black tin is preferable on account of its being less liable to rust. The size of the cylinder for ordinary purposes is nine inches long and four inches diameter turned out and polished on the inside. The piston is of the same metal with the cylinder. It is two inches long $\frac{1}{4}$ inch thick turned and polished so as to fit the inside of the cylinder. A little below the middle and around the inside of the piston is a lip or shoulder projecting $\frac{1}{4}$ inch across the center in a bar $\frac{1}{4}$ inch thick and $\frac{1}{2}$ inch wide faced often the upper side even with the lip for the valve to rest upon. The piston valves are made of leather which is saturated with tallow, cleaned water for oil pastes and covered with suitable plates in the usual form excepting that instead of covers the plates are secured to the leather by brass or iron pins which are made to fit the holes through the plates so closely as not to require riveting. The valves are hung and fastened to the bar of the piston by an iron brace in the form of an inverted T which is laid on the valves along the center of the bar so that the stem or upright part of the T lies perpendicular $1\frac{1}{2}$ inches from the face side and end of the bar of the bar and is hung by a pin to the lower end of the piston rod which is made pointed for the purpose of receiving it. Two screws passing up through the bar and leather into the brace secure the whole together and the valves are thus

hung in the centre. The plate fig. 1. represents the form of the pump. The height from the base A to the cap under the iron is 3 feet, it is 7 inches square at the base and tapers to 6 inches diameter at the top. In the lower end of this stock is a female screw 3 inches diameter, cut up longitudinally, 3 $\frac{1}{4}$ inches in order to receive the male screw formed on the upper end of the lower pipe. To receive one inch deep and 4 inches diameter is cut around the female screw in order to receive the iron band to secure the joint. The base A is 1 $\frac{1}{4}$ inch thick 10 inches wide and 14 inches long champed down about half its thickness at the out edges. In the centre is a hole formed of the same diameter with the female screw in the lower end of the stock. The male screw of the pipe passes through the base and is secured into the stock which secures the base at the point. The cylinder is connected with the pipe below the base at B. a cavity is formed in the end of the pipe of a size suitable to receive the cylinder one inch longitudinally. It is situated with this composition hereafter described for the inner coating to the pipe and the cylinder is placed within it, and confined by banding around the pipe. The Spout C is of cast iron 5 inches long 2 inch bore inside, having a male screw cut at the end by which it is secured to the stock. A lip in the under side extending downward at the out end of the spout forming an aperture through which the water is discharged. The cap D. which is one and a fourth inches thick, having a male screw through the centre of a size suitable for the bridle and piston rod to pass through and being secured to the bottom of the iron is fastened down upon the top of the stock by screws passing through the iron which are fastened opposite each other to the top of the stock. The upper part of the iron has a horizontal projection of 3 $\frac{1}{4}$ inch through which the screw passes perpendicular to which the cap and iron are readily secured to or detached from the stock. Fig. 2. letter F represents the bridle of the pump which is made of iron excepting a short wooden handle which is banded and driven on at the end. The following or bridle G. is constructed with two ears at the top 1 $\frac{1}{2}$ inches apart and the bridle is hung between them by the piston and pin which passes through them all. The dots on each side of the fulcrum are the holes for securing it to the stock. The distance from the piston and pin, which leaves the upper end of the piston rod at the end of the bridle at H. is 5 $\frac{1}{4}$ inches, the bridle in that space being curved downward 20 degrees. The object of this curvature

To answer in a more simple manner the same purpose of the wheel. The piston
rod may be made either of iron or hard wood. Wooden rods when saturated
with the composition above mentioned for the inner coating of the pipe and covered
that the ends with iron attachments are preferable to iron. The pipe below the
cylinder which conveys the water from the well or fountain is attached to the
lower end of the cylinder by a connecting tube of cast iron represented at fig 3.
The body of it is 3 inches long. It is three inches diameter and one fourth inch thick.
It is secured to the wooden pipe in the same manner as the upper end of the
cylinder. The upper end of this tube is made sufficiently large by an offset to re-
ceive the cylinder by a screw. Within this tube are two apertures for the water to
pass through, formed by a bar one half inch wide across the centre. The baffle
for the valve within it is cut the same diameter with the cylinder. So that the
cylinder when secured down closely confines it which forms the baffle, and the
valve, open in the middle. The pipe for ordinary purposes is 4 inches diameter
made of light and porous wood of which white wood is very suitable. It is con-
nected together by means of a male and female screw made to fit each other of
1/8 inch thread. Cut longitudinally on the ends of the pipe to the distance of 3
inches. A small quantity of thick tar is spread on them and both are secured
together to a joint. The end of the pipe however containing the female screw
should first be banded with common inch horse iron. Elbows in the pipe may
be formed whenever necessary, by cutting the ends on such a bent as when put
together will form the angle required. Around the bore and in the joint of the elbow
there, formed is a ring of gum elastic or common india rubber. The elbow
is secured by two screw bolts which pass through both parts on each side of
the hole, at right angles with the joint. A strainer at the bottom of the pipe
is made of wood the same size with the pipe. It is 3 inches long having
a cavity of 3 inches diameter made within it, leaving a head at the lower
end which together with the sides is perforated with small holes. an inch band
on the lower end of the pipe is left extending half its width below to receive the
strainer and connect it to the pipe. To a deep well, the cylinder should be placed
down to within about 20 feet from the bottom, and in all cases where it
is necessary to guard against frost the cylinder should be placed below the
platform so that a metallic drum can be mounted on the pipe above the cyl-

under and sufficiently, below the base to receive no injury from frost. The inside of the pipe is saturated with a composition of two thirds pitch of a similar viscous substance and one third beeswax. These are melted together and passed through the pipe while hot as may be without injury to the materials, the pipe being heated at one end for that purpose and kept gradually rolling while the composition passes through it until the whole inner surface ^{of the pipe} is saturated and coated over. A similar composition for the outside of the pipe is made of pitch and a small proportion of fat. The pipe is placed over a fire prepared for that purpose and kept gradually rolling while the composition is spread on its hot state with a brush. The moment it is spread equally over a given distance, it is laid down and rolled in a bed of sand standing near for that purpose. This operation, repeated until the whole ^{outside} is coated over. The main object of the sand is to prevent its sticking to the hands while handling it. Another method of saturating the pipe is having a boiler constructed for that purpose, to immerse it in the composition in its hot state, and let it remain until it is ^{sufficiently} saturated outside and inside. (What follows is my own invention and not previously known on the above described machine is 1st the general construction of the pump, 2nd the application of the fit of the metallic piston to the cylinder of said pump, 3rd the application of the screw for connecting the wooden pipe or tube. 4th the manner of constructing the elbow of the pipe. 5th the application of the various composition to the pipe or tube.
